[57] CLAIM

The ornamental design for a support surface protector for use with ornamental objects such as vases, as shown and described.

DESCRIPTION

FIG. 1 shows a perspective view of a support surface protector for use with ornamental objects such as vases with an ornamental object shown dotted;

FIG. 2 is a top plan view thereof;

FIG. 3 is a side elevational view thereof along a line drawn between diametrically opposing foot pads; and, FIG. 4 is a bottom plan view thereof.

Fig. 4
